BELT BUCKLE

Robert L. Stevenson, 2226 Old Welsh Road,
Willow Grove, Pa.

Filed Apr. 16, 1963, Ser. No. 273,358
6 Claims. (Cl. 24—77)

This invention relates to buckles and more particularly to buckles suitable for adjustably securing together opposite ends of a flexible belt.

Prior art buckles used to secure both ends of a flexible belt without perforating the belt have one or more disadvantages such as the presence of moving parts in contact with or visible on the exterior surface of the buckle, the visible extension of the adjustable end of the belt beyond the buckle and the necessity of a forming operation and special tools to assemble the buckle. This last mentioned disadvantage has proved to be particularly troublesome in that it precludes the application of mar-resistant finishes such as hard anodized and vitreous enamel coatings to the exterior of the buckle. Such coatings must be applied before the components of the buckle are assembled. If the assembling of the coated components requires a bending or forming operation to hold the components together in working position then the coating are likely to be chipped or cracked, destroying the finish.

It is therefore among the objects of this invention to provide a simple, inexpensive and easily assembled buckle that is adjustable to secure the free end of a belt without mutilating or perforating the belt.

It is a further object to provide a buckle having no moving parts in contact with or visible on the exterior surface thereof and that requires no forming of the components to assemble the buckle.

Another object is to provide a buckle, the details of construction of which will permit the application of a hard, brittle coating to the exterior surfaces thereof.

It is also an object to provide a buckle that will permit the fastening or release of the adjustable end of the belt by the operator using only one hand.

Various other objects and advantages will appear from the following description of one embodiment of the invention, and the novel features will be particularly pointed out hereinafter in connection with the appended claims.

The invention is illustrated in the accompanying drawings in which:

FIGURE 1 is a front elevational view of one embodiment of the buckle of the present invention shown fully assembled and securing both ends of a flexible belt;

FIGURE 2 is a perspective view of the outer shell member taken from the rear;

FIGURE 3 is a perspective view of the inner plate member taken from the rear;

FIGURE 4 is a perspective view of the clamp taken from the rear;

FIGURE 5 is a perspective view of the partially assembled buckle;

FIGURE 6 is a sectional view of the buckle of FIGURE 1 taken on the line 6—6.

In the embodiment of the belt buckle of the present invention illustrated in the drawings there is shown an outer shell member 1 formed of a single piece of metal and having an outer face portion 2 that is rectangular in outline and curved slightly along its longitudinal axis. As seen in FIGURE 2, the top and bottom portions of the outer shell member are bent along first lines parallel with the longitudinal axis of the buckle and rearwardly with respect to the outer face portion and at substantially right angles thereto to form upper and lower flanges 3 and 4. The rearmost portion of upper flange 3 is

2

bent downwardly along a line parallel with said first line at right angles thereto forming a narrow rim 5 extending the length of said flange. In like fashion the rearmost portion of lower flange 4 is bent upwardly forming a rim 6. A downward projection on one side edge of upper flange 3 and an opposed upward projection of lower flange 4 form stops 7 the function of which will become apparent hereinafter.

An inner plate member 10 that is adapted to be loosely inserted within the outer shell member 1 is formed of a unitary piece of metal and is curved along its longitudinal axis with a radius of curvature similar to that of the outer shell member. Top and bottom portions of the inner plate member 10 are bent rearwardly at right angles along lines parallel with the longitudinal axis thereof forming upper and lower plate flanges 11 and 12 which flanges are tapered, that is their edges are arranged on an incline relative to the face of the inner plate. A narrow strip of metal along the side of the inner plate adjacent the narrow ends of the flanges 11 and 12 is bent in a forward direction at right angles thereto, and this strip is serrated, forming forwardly projecting spaced teeth 15. Semi-circular sections cut out of the rear edges of the upper and lower plate flanges 11 and 12 form open-ended slots 13 and 14. These slots are vertically opposed and are preferably located near the widest ends of the flanges but in any event in a position which will be closed by the rims 5 and 6 when the inner plate member is inserted in the outer shell member 1. The inner plate member is rectangular in outline, dimensionally smaller than the outer shell member and is adapted to be inserted in the space defined by the rear surface of the outer shell member and flanges 3 and 4 and rims 5 and 6 through that side of the outer shell member not having the stops 7. The stops 7 located on the opposite side of the outer shell member prevent the insertion or removal of the inner plate member from that side.

The third component of the belt buckle is a metal clamp 20 which is best seen in FIGURE 4. The clamp consists of a lever portion 21 having a tongue 22 and a belt-gripping portion 23 having a gripping edge 24. The tongue 22 is struck from the lever portion 21 and bent at approximately a right angle thereto. The belt-gripping portion 23 is bent from said lever portion 21 through an angle of approximately 100 degrees in a direction opposite to that of the tongue 22. The belt-gripping portion 23 extends substantially the full width of the space between the flanges 11 and 12 of the inner plate member while the lever portion 21 is somewhat narrower so that it may freely pass between the rims 5 and 6 in outer shell member 1 when the clamp 20 is pivoted during operation of the assembled buckle. Located on opposite side edges of the clamp 20 are trunnions 25 extending outwardly from the clamp 20 to engage in the slots 13 and 14 in the flange 11 and 12 of the inner plate member 10 and capable of freely rotating therein. It should be noted that the trunnions must not interfere with the insertion of the inner plate member 10 into the outer shell member 1.

The components of the buckle are assembled together as shown in FIGURES 5 and 6. One end 30 of a flexible woven belt is inserted between flanges 3 and 4 of outer shell member 1 and the end 30 of the belt allowed to protrude a short distance beyond the side edge of the outer shell member opposite the edge adjacent the stops 7. The inner plate member 10 is lined up with the outer shell member preparatory to insertion therein in such a manner that the side edge of the inner plate member bearing the spaced teeth 15 will be inserted first into the outer shell member and the spaced teeth are placed against the

rear surface of the belt near the end thereof. The inner plate member is then inserted between flanges 3 and 4 of the outer shell member with upper plate flange 11 being subjacent to flange 3 and lower plate flange 12 being suprajacent to flange 4. With the end of the belt thus positioned between the outer shell member and the inner plate there is created a tight frictional fit between these parts. Tapered flanges 11 and 12 of the inner plate member also contribute toward increasing the frictional engagement between the outer shell, belt end, and inner plate member. The spaced teeth 15 prevent the end of the belt from being pulled free from its position in response to any strain thereon. In addition, once the inner plate member has been partially inserted between the flanges of the outer shell it is possible by pulling on the belt to draw the inner plate into position behind the outer shell member. The inner plate member 10 is in position when it is completely hidden within the outer shell member 1 and in the illustrated embodiment when the side edges of its flanges 11 and 12 come to rest against stops 7 of the outer shell member preventing any further movement in the direction of pull normally exerted by the belt, i.e., in a direction opposite to or away from the end of the belt.

Prior to insertion of the inner plate member within the outer shell, the clamp 20 is placed in position on the inner plate member with trunnions 25 extending into the open slots 13 and 14 and with lever 21 directed toward the side edge of the inner plate carrying the spaced teeth 15. When the inner plate is in position within the outer shell member the clamp is pivotally fixed in position by the trunnions extending into the slots, the open ends of which are closed by rims 5 and 6.

The buckle is now securely fixed to the end 30 of the belt and the adjustable end 31 is inserted between the back surface of the inner plate and the clamp 20. An application of pressure on the lever moving it toward the back surface of the inner plate causes the gripping member to swing into and bear against the belt, squeezing the belt tightly against the back surface of the inner plate. This inward pressure on the lever continues until the lever rests against the belt and the gripping member has moved through and slightly beyond a plane perpendicular to the belt. When so positioned the adjustable end 31 of the belt is tightly gripped and the force normally applied to this end of the belt tending to pull this belt end away from the buckle and tending to pull the gripping member open is resisted by the lever which bears against the belt. In addition, any force exerted by the belt end 31 tending to pull on the belt gripping portion 23 will cause the ends of the lever portion 21 to engage the belt surface with increasing force to increase the resistance of the clamp against sliding of the belt.

The adjustable end of the belt is released by applying pressure on the rearwardly directed tongue, causing the lever to swing rearwardly with respect to the face of the buckle.

As can be seen from the foregoing description, the buckle of the present invention is assembled without any bending or forming of parts to complete the assembly, thereby permitting the application of a hard brittle coating to the exterior surfaces of the components. In fact, no tools at all are required to assemble or disassemble this buckle. In addition the buckle in use presents an exterior appearance free from moving parts as seen in FIGURE 1. Furthermore, the adjustable end of the belt is hidden from view, further enhancing the clean, neat appearance of the buckle. Finally, the buckle of the present invention can be disengaged by one hand, leaving the other hand free for other activity. This feature is particularly useful when driving a car or other such activity where the operator may desire to loosen his belt for comfort while the car is continuing in operation.

The foregoing description is illustrative only, and it will be understood that various changes in the details,

materials, steps and arrangements of parts, which have been herein described and illustrated in order to explain the nature of the invention, may be made by those skilled in the art within the principle and scope of the invention as expressed in the appended claims.

I claim:

1. In a belt buckle for adjustably securing the ends of a flexible belt, the combination of:
  - (a) an outer shell member having rearwardly directed and spaced apart upper and lower retaining means,
  - (b) an inner plate member insertable behind said outer shell member and having rearwardly extending flanges engaged by said retaining means, said inner plate member frictionally held within said outer shell member when one end of a belt is disposed and held therebetween, said flanges being provided with opposed open-ended slots therein closed by said retaining means when said inner plate member is inserted in said outer shell member, and
  - (c) clamping means mounted in said slots to releasably clamp the other end of said belt against said inner plate member.
2. In a belt buckle for adjustably securing the ends of a flexible belt, the combination of:
  - (a) an outer shell member having rearwardly directed and spaced apart upper and lower retaining means,
  - (b) an inner plate member insertable behind said outer shell member and having rearwardly extending spaced apart upper and lower flanges slideably engaging said retaining means, said flanges being tapered to provide a wedging action between said inner plate member and the inside surface of said outer shell member to clamp one end of a belt therebetween as said inner plate member is inserted into said outer shell member and said flanges engage said retaining means, said flanges being provided with vertically opposed open-ended slots therein adapted to be closed by said retaining means on said outer shell member when said inner plate member is inserted in said outer shell member, and
  - (c) clamping means pivotally seated in said slots to releasably clamp the other end of the said belt against the rear surface of said inner plate member, said clamping means being freely removable from said slots when said inner plate member is not inserted in said outer shell member.
3. In a belt buckle for adjustably securing the ends of a flexible belt, the combination of:
  - (a) an outer shell member having rearwardly directed and spaced apart upper and lower retaining means,
  - (b) an inner plate member insertable endwise behind said outer shell member and between said retaining means, and having rearwardly extending spaced apart upper and lower flanges slideably engaging said retaining means, said inner plate member adapted so as to be frictionally held within said outer shell member when one end of a belt is disposed and held therebetween, the belt engaging portion of said inner plate member being provided with means for gripping said belt, each of said flanges being provided with an open-ended slot which slots are in substantially vertical alignment and which are closed by said retaining means when said inner plate member is inserted within said outer shell member, and
  - (c) clamping means pivotally mounted in said slots to releasably clamp the other end of said belt against the rear surface of said inner plate member, said clamping means being freely removable from said slots when said inner plate member is not inserted in said outer shell member.
4. A belt buckle according to claim 3 having a stop means on said outer shell to limit movement of said inner plate member in the direction of insertion into said outer shell member and wherein said flanges are tapered so as to exert a wedging action to increase the frictional en-

gagement of said inner plate member within said outer plate member.

5. In a belt buckle for adjustably securing the ends of a flexible belt, the combination of:

(a) an outer shell member having spaced upper and lower flanges extending rearwardly with respect to the face thereof and at substantially right angles thereto, said upper shell flange having a rim extending downwardly along its rear marginal edge, said lower shell flange having a rim extending upwardly along its rear marginal edge, 5

(b) an inner plate member adapted to be inserted in said outer shell member and having rearwardly extending plate flanges along the top and bottom edges thereof capable of slideably engaging said upper and lower shell flanges, said inner plate member being adapted so as to be frictionally held within said outer shell member when one end of a belt is disposed and held therebetween, the belt engaging portion of said inner plate member being provided with means for gripping said belt, said plate flanges being provided with opposed open-ended slots therein, the open ends 15

of said slots adapted to be closed by the rims of said outer shell member when said inner plate member is inserted therein, and

(c) clamping means mounted in said slots to releasably clamp the other end of said belt against the rear surface of said inner plate member, said clamping means being freely removable from said slots when said inner plate member is not inserted in said outer shell member.

10 6. A belt buckle according to claim 5 having a stop means on said outer shell to limit movement of said inner plate member in the direction of insertion into said outer shell member.
